UNITED STATES PATENT OFFICE.

ALONZO GALLOWAY DECKER, OF TOWSON, MARYLAND, ASSIGNOR TO THE BLACK & DECKER MANUFACTURING COMPANY, OF TOWSON, MARYLAND, A CORPORATION OF MARYLAND.

DESIGN FOR A HANDLE FOR A PORTABLE POWER-DRIVEN TOOL.

Application filed July 25, 1925. Serial No. 14,222. Term of patent 14 years.

To all whom it may concern:

Be it known that I, ALONZO GALLOWAY DECKER, a citizen of the United States of America, and resident of Towson, county of Baltimore, State of Maryland, have invented a new, original, and ornamental Design for a Handle for Portable Power-Driven Tool, of which the following is a specification.

In the drawing—

I have illustrated a handle in accordance with my invention and shown in dotted lines a fragment of a portable power driven tool to which the handle is attached.

Figure 1 is an elevation showing my new design.

Figure 2 is a top plan of the same.

I claim:

The ornamental design for a handle for a portable power-driven tool substantially as shown.

Signed by me at Towson, county of Baltimore, State of Maryland, this 22 day of July, 1925.

ALONZO GALLOWAY DECKER.
